DANDY ROLL

Earl E. Berry, Beloit, Wis., assignor to Beloit
Iron Works, Beloit, Wis., a corporation of Wis-
consin

Application February 2, 1931, Serial No. 512,770

8 Claims. (Cl. 92—48)

This invention relates to paper making machines and has special reference to the construction and mounting of the dandy roll thereof.

The dandy roll is rotatably supported above the sheet being formed in the paper machine somewhere between the suction boxes, one or more thereof being positioned on each side of the roll. The function of the dandy roll is to better the formation of the sheet. A further function of this roll is to reproduce in the sheet certain desirable characters or designs appearing on the roll by means of water marking. This should not, however, be confused with undesirable water marks caused by defective dandy roll construction or operation presently to be described. Because of the delicate condition of the sheet at this point, it is necessary to keep the roll very light, and also very rigid. Any slight variation in the operation of the roll will cause a defective sheet.

20 Slight distortions of the roll result in serious defects in the resultant product and require the replacement of the roll. At the present time, the average life of the roll on large high speed machines is usually not more than a year to a year and one-half. The rolls are expensive to manufacture and this regular replacement represents a serious loss to the paper manufacturer.

The dandy rolls now customarily employed upon paper making machines are formed of a network or lattice of brass rods, ribbons, or wires, soldered together at frequent intervals and over-laid with a cover of fine mesh wire cloth. Each end of the roll is provided with a head of heavy section metal having a trunnion axially positioned with respect to the roll for rotatably supporting the roll in suitable bearings. At least one trunnion is provided with an opening to receive a pipe connected to a steam or air shower within the roll. The purpose of this shower is to drive the water out of the interstices of the wire cloth cover and prevent the water from following the roll. If the water is allowed to follow the outside surface it makes a water mark in the sheet of paper being formed. In order to bring this shower nearer to the surface of the roll than the longitudinal axis thereof of the pipe upon which the shower is supported must be bent downward through an angle of 90° or thereabouts. A serious objection to this construction is that when steam is used this provides a trap in which any condensed water is caught and carried outward by the steam against the surface of the roll thereby supplying a certain quantity of water to the roll whereby a water marked sheet will result.

55 In the prior art a second steam or air shower

is also positioned to direct a flow of steam or air against the outside surface of the roll at the point at which it leaves the surface of the sheet. The purpose of this shower is to prevent the water of the sheet from raising up along the surface of the roll by capillarity and the movement of the roll, by driving it downward against the sheet. It will be seen that as the diameter of the rolls increase it will be necessary to place the latter farther and farther away from the line at which the roll leaves the sheet, the efficiency of the spray being proportionately decreased. The difficulty with the use of this type of spray lies in the fact that it is impossible to direct the steam directly to the source of the trouble. The shower is palliative rather than remedial.

In recent years both the size and the speed of paper machines have been considerably increased. In keeping with this both the length and the speed of rotation of the dandy rolls has been increased. In order to attain the proper rigidity and strength of roll it has been necessary to go to dandy rolls of considerably larger diameter. It has been found that, due to the greater curvature of the larger rolls, there is a greater tendency for the water to follow the surface of the roll. This is doubtless due to the difference in angle at which the roll leaves the sheet. It has, therefore, become necessary to increase the efficiency of the showers in order to break down the film of water and prevent the water from following the roll. A steam shower is most generally used for this purpose and when positioned to best advantage inside of the roll the temperature is such as to soften the solder used in securing the roll together, thereby weakening its structure and causing it to become easily distorted.

Thus there are three very serious objections to dandy rolls as they are now customarily manufactured. The rolls are soldered together and this solder becomes softened by the steam directed against the surface of the roll for the purpose of preventing the water from following the roll. This so weakens the metal joints that the roll is easily distorted and also prevents the advantageous use of steam of higher temperature. A second objection is that the dandy rolls must be made of large diameter in order to be sufficiently strong and rigid to withstand the torsional stresses to which they are subjected. This increase in size of the roll increases the tendency of the water to follow the roll and increases the difficulty of preventing this phenomena. A third objection is that the rolls are supported upon

trunnions axially positioned at their ends and are driven by contact of the roll with the sheet. This means that they are driven from the lattice work in which the solder is already softened by the high temperature of the steam, and are held at their ends. At best, there is a certain amount of friction at the trunnions, and quite often some condition arises in which there is unusual resistance to the rotation of one of the 10 trunnions, such for example, as the binding of the steam pipe and trunnion, whereby the roll becomes badly distorted.

Various attempts have been made during a long period of years to remedy these conditions 15 but until the present invention, no satisfactory solution has been found. In solving the problem it has been necessary to make sweeping and revolutionary changes in the dandy roll and its construction to produce a structure having all of 20 the characteristics desired of such a roll. It has been necessary to employ a metal having considerably greater modulus of elasticity and strength than that previously employed. It has been necessary to employ metal substantially corrosion resistant under the conditions of use. It 25 has also been necessary to devise improved means for driving or rotating the roll.

One of the principal objects of my invention is the provision of a dandy roll having a lattice 30 of high strength corrosion resistant material wherein the metal of the frame is welded together at the lattice intersections.

Another object of the invention is the provision of a dandy roll having improved means for supporting the roll and for raising the roll from 35 the sheet.

Another object of the invention is the provision of means for driving a dandy roll.

Other objects and attendant advantages will 40 become apparent to those skilled in the art from the following description and the accompanying drawings in which—

Figure 1 is a side elevation of the dandy roll and support showing one of the table rolls and 45 means for supporting the table roll;

Fig. 2 is an end elevation of a dandy roll and dandy roll support;

Fig. 3 is a fragmentary view partly in section showing the manner in which the dandy roll is 50 constructed;

Fig. 4 is a vertical section on the line 4—4 of Fig. 1; and

Fig. 5 is a diagrammatic view illustrating the 55 effect of the dandy roll diameter upon the tendency for the water to follow the surface of the roll.

The present invention contemplates a dandy roll of smaller diameter than would normally be used in the prior art, considering the size and 60 speed of the machine, the frame being fabricated of stainless steel or similar corrosion resistant metal of high physical properties, and the intersections of the metal of the frame being connected together by means of welding. Any 65 of the well known methods may be employed in manufacturing a roll of this character. Customarily the ends of the roll are formed of comparatively heavy section metal and joined by a truss forming part of a lattice of wires brought 70 into contact at frequent intervals the truss wires being connected together at the points of contact in order to make the roll rigid. Various arrangements of the wire are employed by different manufacturers to form the lattice and, doubt- 75 less, any one of these may be satisfactorily used.

The primary requisites of this lattice are that it be rigid, light in weight, and open in structure.

The invention further contemplates means for supporting the roll at the periphery near each end so that the end of the roll is open to permit 80 the positioning of a spray or sprays advantageously therein.

Referring first to Figs. 1 and 2, the numerals 7 and 8 designate a pair of standards supported upon opposite sides of the paper machine wire 9 upon legs 11 and 12 between suction boxes 10 and 10a. The upper ends of the legs have sockets 13 and 14 to receive the lower ends of the standards. Brackets 16 and 17 are connected to the upper ends of the standards 7 and 8 by means of sleeves 18 and 19 and extend along the sides of the wire 9 in the same direction. Sleeves 21 and 22 are positioned on the standards 7 and 8 intermediate the ends thereof and serve to support pulleys 23 which extend inward from the standard to points near opposite sides of the wire 9. Arms 24 and 25 are rotatably supported at one end upon the sleeves 18 and 19 adjacent to the standards 7 and 8 and extend in a direction slightly above and parallel to the brackets 95 16 and 17. The outer ends 26 and 27 of the arms 24 and 25 pass through substantially a right angle and extend downward to rotatably support pulleys 28 and 29 in substantially the same horizontal plane as the pulleys 23 but spaced therefrom in the direction of travel of the wire 9. Openings 31 are provided in enlarged portions 32 of the arms 24 and 25 and serve to slidably support blocks 33 and 34. Springs 35 are positioned within the openings 31 and act between the blocks 105 33 and 34 and heads 36 supported upon adjusting screws 37 and 38. The blocks 33 and 34 support the arms 24 and 25 upon eccentric cams 39 and 41, positioned upon a shaft 42 extending between the outer ends of the brackets 16 and 17 and 110 serving to hold the same in spaced relation, the position of the cams 39 and 41 normally determining the elevational position of the pulleys 28 and 29. A handle 43 is fixedly secured to one end of the shaft 42. Rotation of the handle 43 115 serves to rotate the eccentric cams 39 and 41 and thereby either raise or lower the outer ends of the arms 24 and 25 and the pulleys 28 and 29 for the purpose of lifting the dandy roll from the sheet on the wire 9 as will presently be described. 120 The normal operating position of the pulleys 28 and 29 is varied through rotation of the screws 37 and 38, the pulleys being raised when the screws are turned into the portions 32 and lowered when the screws are turned out of these 125 portions.

A table roll designated generally by the numeral 44 is positioned beneath the wire 9 and serves to support the wire. The roll 44 is rotatably supported by means of bearings 45 and 46 rotatably receiving trunnions 47 and 48 which are fixedly secured to the roll 44. Blocks 49 and 51 support the bearings 45 and 46 at a desired elevation. The wire 9 of the paper machine rests upon the roll 44 and through its movement serves 130 to rotate the latter. Belts 52 and 53 of suitable design are trained over opposite ends of the roll 44, the belt 52 being also trained over one of the pulleys 23 and over the pulley 28 and the belt 53 being trained over the spaced pulleys 23 145 and 29.

The spaced pulleys and the belts serve to provide a sling to support opposite ends of a dandy roll designated generally by 54 which is provided at 150 opposite ends with end sections 55 and 56 of

comparatively heavy section metal. Circumferential grooves 57 and 58 are formed in the end sections 55 and 56 to receive the belts 52 and 53 as shown in Figs. 1 and 2.

5 It will be seen that upon rotation of the table roll 44 the belts 52 and 53 will be driven and will rotate the dandy roll 54 at substantially the same speed. It will further be seen that the dandy roll may be almost entirely supported upon 10 the belts 52 and 53 and only have sufficient contact with the sheet lying upon the wire 9 to perform its necessary functions. The pulleys 23 and 28 and the pulleys 23 and 29 are so spaced with respect to each other as to bear against the periphery of the end portions 55 and 56, respectively, thereby preventing lateral movement of the ends of the roll to prevent wabbling of the roll during its rotation. When it is necessary to lift the roll 54 from the sheet on the wire 9 the 15 crank 43 is rotated whereby the pulleys 28 and 29 are lifted, thereby tightening the belt and lifting the roll from the sheet.

20 Brackets 59 and 61 are positioned upon the upper sides of the bearings 45 and 46 and serve to support yokes 62 and 63 which are adjustably secured thereon by means of bolts 64. A steam shower pipe 65 is positioned within the yokes 62 and 63 and passes through the inside of the dandy roll from end to end, one end 25 thereof being provided with a cap 66. Yokes 62 and 63 permit the shower pipe 65 to be conveniently removed from the dandy roll as will be apparent.

25 Referring now to Fig. 3, the dandy roll consists of a frame of comparatively heavy section circular end portions 55 and 56, which may advantageously be made of stainless steel or other high strength corrosion resistant metal, connected by a truss forming part of a lattice designated generally by the numeral 67. The truss 30 consists of two layers of wire of stainless steel or other high strength corrosion resistant metal fabricated into a cylindrical roll. The first layer is formed of a series of wires 68 having a general circumferential direction but curved from side 35 to side as shown in Fig. 3, succeeding loops being brought into contact at various points about the circumference of the roll as shown at 69. The wires 68 are welded together by any suitable welding method at these points of contact, so as to produce a rigid frame-work. The next layer is formed by longitudinal wires 71 circumferentially spaced upon the frame-work formed by the wires 68. These wires are welded to the wires 40 68 at each point of contact throughout the entire length of the roll.

45 A third layer of wires is formed over the truss wires 68 and 71 from circumferential wires 72 longitudinally spaced upon the wires 71, the 50 three layers of wires forming a network or lattice. These may, or may not be welded at each point of intersection with the wires 71, depending upon the desire of the manufacturer.

55 It is common, however, to mill or grind a series of slots or depressions in the longitudinal wires 71 in the form of a helix to receive the wires 72, which may advantageously consist of a single wire wound tightly in the slots from end to end of the truss. The slots hold the wires 72 in position and prevent longitudinal movement thereof. This construction eliminates soldering or welding the wires 72 to the truss, though they may be welded if desired. The cover 73 consisting of wire mesh cloth similar in 60 texture to the wire 9, is then tightly stretched

over the wires 72 and the ends thereof fastened together by any suitable means, as, for example, by stitching, lacing, or the like. This cover is preferably formed of wire cloth having a chemical composition similar to that of the wire frame work but, if desired, the usual brass cloth may be employed for the purpose since the cloth need not be secured to the frame through soldering or welding operations.

65 Fig. 4 shows the manner in which the dandy roll cooperates with the sheet being formed, designated by the numeral 74. Referring also to Fig. 5, it will be seen that the water tends to follow the surface of the dandy roll as the latter moves along the sheet. This difficulty increases as the diameter of the dandy roll increases and as the speed of rotation thereof increases. Therefore, in order to prevent this phenomenon the shower pipe 65, previously described, is inserted in the dandy roll and provided with sprays 75 to permit the escape of steam or air from the pipe. A baffle 76 is positioned to deflect the gas emerging from the sprays 75 against the inside of the roll along the line at which the roll leaves the sheet. The 70 spread of the shower may advantageously extend a short distance each side of this line. The baffle 76 is provided with a groove 77 adapted to engage a projection 78 on the pipe 65 so that the baffle may be removed by sliding the same 75 endwise along the pipe until the groove 77 disengages the projection 78. While other types of showers may be employed, that shown in the accompanying drawings is deemed preferable, a more complete description of which may be found 80 in United States Letters Patent No. 1,788,469. It will be seen that these sprays will tend to drive the water back into the sheet and away from the 85 surface of the roll.

90 Because of the manner in which the roll is supported, which permits the ends of the roll to be open, the pipe 65 may be placed at a point relatively close to the circumference of the roll so that the heat of the gas may be concentrated at the desired point on the surface of the roll, 95 and the mechanical energy of the moving gas utilized to a maximum extent. Furthermore, it will be seen that since the metal intersections of the lattice are welded the steam employed for the sprays may be brought to any desired temperature without danger of so weakening the roll that distortion thereof will result. Furthermore, the shower pipe may be made of considerably larger diameter in order to accommodate 100 a greater amount of steam without, in any way, increasing the difficulty of rotating the roll as has heretofore been necessary. In other words, 105 since the shower pipe does not pass through the roll supporting means, the element of friction between these members, is not a factor.

110 By my invention the dandy rolls may be made considerably smaller in diameter and of lighter weight than has heretofore been possible whereby the roll will be made to leave the sheet at a considerably greater angle than heretofore, 115 thereby reducing the tendency of the water to follow the surface of the roll and decreasing the difficulty of preventing this trouble.

120 Even when rolls are made of the same size and cross-section of metal, those made according to my invention will have substantially less weight, since brass or bronze weighs about .31 125 less per cubic inch, while stainless steel weighs about .28 pounds per cubic inch. In addition to the difference due to the difference in weight of 130

the metal, there is the weight of the solder to be considered.

My invention further eliminates the troubles resulting from the use of solder for connecting the various portions of the lattice. Superheated steam at any temperature may be employed without danger of weakening the joints between the metal and substantially no chemical body will react with the welded portion which does not at the same time effect the entire roll.

The provision of welded joints not only eliminates the use of solder but results in joints of much greater strength and rigidity than could possibly be obtained by soldering. Numerous attempts have been made to weld brass, bronze and the like for this purpose but no satisfactory results have ever been obtained.

My improved manner of mounting the dandy roll proper serves to substantially eliminate all torsional strain on the lattice of the roll, since the roll is driven at substantially the same peripheral speed as the sheet with which the roll comes in contact.

The invention, because of the use of metal of high modulus of elasticity and because of welding of the points of contact of the truss, prevents the so-called whipping or jumping of the roll. This is a phenomenon which results from the development of wider and higher speed machines. In other words, when the dandy rolls are employed on wide high speed machines, there is a pronounced tendency for the cylinder of the roll to whip, thereby resulting in an uneven sheet and in excessive wear on the wire of the machine which naturally results from the roll pressing more on one part of the wire than on another. Because of the high modulus of elasticity of the metal, the deflection customary in this type of rolls is substantially eliminated.

A further decided advantage of the present construction lies in the fact that it permits of the utilization of an open end roll without having it become egg shaped or flattened after a short period of use. It has heretofore been impractical to utilize an open end roll because of the fact that this change in shape occurred. In other words, it has heretofore been necessary to provide a spider or other stiffening means on the ends of the roll in order to prevent this change in shape in as far as possible. The present invention permits the practical utilization of such a construction.

While I have illustrated a specific embodiment of my invention I am aware that numerous alterations and changes may be made therein without departing from the spirit of the invention and the scope of the appended claims in which—

I claim:

1. In a paper making machine having a wire, a dandy roll, means for rotatably supporting said roll at the periphery near each end thereof, and means for driving said roll at a peripheral speed substantially equal to the linear speed of said wire.

2. In a paper making machine, a dandy roll adapted to engage the surface of a sheet being formed, an endless belt at each end of said roll adapted to form a sling to support the ends of said roll, means for preventing lateral movement of the ends of said roll, and means for driving said belts to rotate said roll.

3. In a paper making machine, a dandy roll adapted to engage the surface of a sheet being formed, an endless belt at each end of said roll adapted to form a sling to support the ends of said roll, means for preventing lateral movement of the ends of said roll, means for lifting said roll from said sheet, and means for driving said belts to rotate said roll. 80

4. In a paper making machine, an open end dandy roll adapted to engage the surface of a sheet being formed, means for rotatably supporting the roll at the periphery thereof near each end, a stationary spray pipe in said roll positioned to direct a spray of gas through said roll along the line at which the latter leaves the sheet. 85

5. In a paper making machine, an open end dandy roll adapted to engage the upper surface of a sheet being formed, a roll below said sheets and driven therewith, spaced pulleys above said sheet at each side thereof and endless belts trained over said lower roll and over said pulleys adapted to support the ends of said dandy roll between said spaced pulleys, the pulleys at each end being spaced to bear against opposite sides of said dandy roll to prevent lateral movement of said end, and said belt serving to drive said dandy roll. 90

6. In a paper making machine, an open end dandy roll adapted to engage the upper surface of a sheet being formed, a roll below said sheets and driven therewith, spaced pulleys above said sheet at each side thereof and endless belts trained over said lower roll and over said pulleys adapted to support the ends of said dandy roll between said spaced pulleys, the pulleys at each end being spaced to bear against opposite sides of said dandy roll to prevent lateral movement of said end, and said belt serving to drive said dandy roll, and means for raising said dandy roll from said sheet. 100

7. In a paper making machine, an open end dandy roll adapted to engage the upper surface of a sheet being formed, means for rotatably supporting said rolls comprising an upright member at each side of said sheet, a pulley on each of said uprights, a pulley spaced from each of said pulleys, an arm rotatably supported near each upright each arranged to support one of said second pulleys in spaced relation to said first mentioned pulleys, resilient means for maintaining said arms in desired positions, a roll positioned beneath said sheet, endless belts trained over the pulleys at each side of said sheet and over said lower roll, adapted to support the ends of said dandy roll between said spaced pulleys, and means for raising and lowering said arms to raise and lower said dandy roll, said lower roll being driven with said sheet and serving to drive said dandy roll. 110

8. In a paper making machine, an open end dandy roll adapted to engage the surface of a sheet being formed, means for rotatably supporting the roll at the periphery thereof near each end, a stationary spray pipe entering said roll near the periphery thereof and positioned in close proximity to the inner surface of the roll substantially along the line at which the roll leaves the sheet to direct a spray of gas through said roll along the line at which the latter leaves the sheet. 120

EARL E. BERRY.
